John F. Rathbone, of Albany, N.Y.
Letter Patent No 384, dated Jan 10th 1851

The Schedule referred to in these Letters Patent and making part of the same
To whom it may concern

Be it known that I John F. Rathbone of the City of Albany of State of
New York have produced a new ornamental design for a six plate stone
and I do hereby declare that the annexed and accompanying drawings are
full and accurate delineations of the ornamental parts of said stone
with their several ornaments, the end and side plate not shown in the drawing
and where portions of the plates are shown, the portions not shown with
their ornaments being similar to, & similarly & symmetrically ornamented
with, the portions shown

What I claim as my production and desire to secure by Letters Patent, is the
combination and arrangement of ornamental figures and forms, re-

Res. 384

presented in the accompanying drawings forming together an ornamental
design for a fireplace stove
